(57) **ABSTRACT**

A new cultivar of *Helenium*, 'Short 'n' Sassy', characterized by its dwarf plant habit; reaching 45 to 56 cm in height, its early commencement of bloom with new blooming stems continuously produced that rise above the older spent blooms and its inflorescences with ray florets that are a blend of yellow and red in color creating a yellow and orange effect.

2 Drawing Sheets

1

Botanical classification: *Helenium autumnale*.
Variety denomination: 'Short 'n' Sassy'.

BACKGROUND OF THE INVENTION

The present invention relates to a new and distinct cultivar of *Helenium autumnale* and will be referred to hereafter by its cultivar name, 'Short 'n' Sassy'. 'Short 'n' Sassy' represents a new *Helenium*, an herbaceous perennial grown for landscape use.

The Inventor discovered the new *Helenium* as a naturally occurring whole plant mutation in summer of 2009 in a garden in Mount Vernon, Wash. The parentage is unknown.

Asexual reproduction of the new cultivar was first accomplished by stem cuttings by the Inventor in Mount Vernon, Wash. in August of 2009. The characteristics of this cultivar have been determined to be stable and are reproduced true to type in successive generations.

SUMMARY OF THE INVENTION

The following traits have been repeatedly observed and represent the characteristics of the new cultivar. These attributes in combination distinguish 'Short 'n' Sassy' from other cultivars of *Helenium* known to the Inventor.

1. 'Short 'n' Sassy' exhibits a dwarf plant habit; reaching 45 to 56 cm in height.
2. 'Short 'n' Sassy' blooms 2 to 3 weeks earlier than is typical of most cultivars of *Helenium autumnale*.
3. 'Short 'n' Sassy' continues to produce new bloom stalks that rise above the older spent blooms; a characteristic not typically observed in cultivars of *Helenium autumnale*.
4. 'Short 'n' Sassy' exhibits inflorescences with ray florets that are a blend of yellow, and red creating a yellow and orange effect.

'Short 'n' Sassy' can be most closely compared to the cultivars 'Mardi Gras' (U.S. Plant Pat. No. 15,124) and 'Pipsqueak' (not patented). 'Mardi Gras' is similar to 'Short

2

'n' Sassy' in having flowers that are similar in color. 'Mardi Gras' differs from 'Short 'n' Sassy' in being about twice as tall and in blooming 2 to 3 weeks later in the growing season. 'Pipsqueak' is similar to 'Short 'n' Sassy' in having a dwarf plant habit. 'Pipsqueak' differs from 'Short 'n' Sassy' in having ray florets that are solid yellow in color and in blooming later in the season.

BRIEF DESCRIPTION OF THE DRAWING

The accompanying colored photographs illustrate the overall appearance and distinct characteristics of the new *Helenium*. The plants in the accompanying photographs were taken of a one year-old plant of 'Short 'n' Sassy' as grown in a two-gallon container in Mount Vernon, Wash.

The photograph in FIG. 1 depicts a plant of 'Short 'n' Sassy' in bloom.

The photograph in FIG. 2 shows a close-up of the inflorescences of 'Short 'n' Sassy'. The colors in the photograph may differ slightly from the color values cited in the detailed botanical description, which accurately describe the colors of the new *Helenium*.

BOTANICAL DESCRIPTION OF THE PLANT

The following is a detailed description of one-year-old plants of the new cultivar as grown in two-gallon containers in Mount Vernon, Wash. The phenotype of the new cultivar may vary with variations in environmental, climatic, and cultural conditions, as it has not been tested under all possible environmental conditions. The color determination is in accordance with The 2007 R.H.S. Colour Chart of The Royal Horticultural Society, London, England, except where general color terms of ordinary dictionary significance are used. General description:

Blooming period.—Commences bloom early in mid summer and blooms for 8 to 10 weeks in Mount Vernon, Wash.
